LLP[57] **CLAIM**

The ornamental design for a public toilet, as shown and described.

DESCRIPTION

FIG. 1 is a front perspective view of a public toilet showing my new design.

FIG. 2 is a front elevational view thereof.

FIG. 3 is a side elevational view thereof.

FIG. 4 is a rear elevational view thereof; and,

FIG. 5 is a top plan view thereof.

The inscription illustrated in broken lines is for illustrative purposes only and forms no part of the claimed design.
